UNITED STATES PATENT OFFICE.

FERDINAND BUSSE, OF BERLIN, GERMANY.

SELF-WINDING ELECTRIC CLOCK.

Application filed December 11, 1923. Serial No. 679,937.

To all whom it may concern:

Be it known that I, FERDINAND BUSSE, a citizen of Germany, residing at Berlin, in the State of Prussia, Germany, have invented certain new and useful Improvements in Self-Winding Electric Clocks; and I do hereby declare the following to be a full, clear, and exact description of the invention, such as will enable others skilled in the art to which it appertains to make and use the same.

My invention relates to improvements in self-winding electric clocks, and while useful for various purposes, is particularly adapted for use in connection with automobile clocks. More particularly my invention relates to clocks in which an electric motor is operated at intervals to wind the clock, the circuit through the motor being opened and closed by the movement of the spring barrel. One of the objects of the improvements is to provide a clock of this class in which the spring barrel or mechanism connected therewith is normally relieved of the switch operating member controlled thereby, said switch member being brought into engagement with the barrel or associated part at the moment the circuit is to be closed for winding the clock. With this object in view the invention consists in providing a member such as a lever for normally holding the switch operating member out of engagement with the spring barrel or mechanism connected therewith, which lever is rocked by the spring barrel or a part movable therewith slightly before the clock is to be rewound. By thus relieving the movement of the clock of the pressure of the switch mechanism a large operating member may be provided which does not require nice finish in the manufacture as is the case with parts of the size of the parts of a clock. Furthermore the switch operating mechanism may be made independent of the clock mechanism and mounted on a frame of its own, and a small size movement of normal construction may be provided, which is mounted on the said frame and needs small changes of construction for adapting the same to the winding mechanism.

Another object of the improvements is to provide means for arresting the clock in case the winding mechanism fails to operate. In one embodiment the switch operating

lever acts as a locking member if it has been set for closing the motor circuit and the clock mechanism is not rewound. Other objects of the invention will appear from the following description of the clock.

In the drawings,

Fig. 1, is a sectional elevation of the winding mechanism showing parts of the movement of the clock,

Fig. 2, is a section taken on the line 2—2 of Fig. 1 and looking in the direction of the arrows,

Fig. 3, is a partial elevation looking from the left in Fig. 1 and showing the dial,

Fig. 4, is a detail sectional view taken on the line 4—4 of Fig. 1 and looking in the direction of the arrow,

Fig. 5, is an elevation similar to the one shown in Fig. 2 and showing a modification, and

Fig. 6, is a section taken on the line 6—6 of Fig. 5.

In the example shown in Figs. 1 to 4 the clock is disposed in a case comprising a cylindrical wall *s* secured to a reflector ring *b*¹ and a lid *s*¹. To the ring *b*¹ a ring *b* is secured which is formed with an inner flange *b*² adapted to have a clock movement of normal construction mounted therein. To the disk *b* two posts *p* are secured which provide a support for a bridge consisting of two plates *p*¹.

Any preferred movement may be provided within the ring *b*. The figures show only the spring barrel *c*, the gear teeth *d* provided thereon, the spring arbor *c*¹ and the balance *m*. To the arbor *c*¹ a gear wheel *e* is secured which is in mesh with a pinion *f* connected by a suitable transmission gearing *g* with an electromotor *r*. The transmission gearing is mounted on the bridge *p*¹, and the electromotor is mounted within the rear part of the case *s* in front of the lid *s*¹, so that it may be readily dismounted after removing the lid. To permit such dismounting independently of the transmission gearing *g* a coupling is provided between the motor shaft *r*¹ and the shaft *g*¹ of the gearing, which coupling consists of arms *r*² and *g*² secured to the said shafts and loosely connected with each other by a pin *g*³ secured to the arm *g*² and engaging in a bore of the arm *r*². Current is supplied to the electromotor by binding posts *t* provided on the lid *s*¹, and the motor circuit

includes insulated spring contacts t^1 connected respectively by a lead z and a slide arm h^3 with a circuit make-and-break device consisting of a cam disk h^1 and a finger h^2 .

- 5 The gear d is in engagement with the movement of the clock (not shown). In addition it is in mesh with a gear i of even diameter and number of revolutions, which gear is mounted on the ring b and carries a 10 disk j formed with a notch j^2 . On a spindle k^2 a spring pressed lever k is mounted which is provided at its free end with a nose k^3 adapted for engagement by a spring pressed pawl l mounted on a spindle l^2 , the spindles 15 k^2 and l^2 being rockingly mounted on the ring b and the bridge p^1 . The lever k carries a pin k^4 normally held out of contact with the disk j , but adapted for engagement therewith and with the notch j^2 upon the release 20 of the lever k by the pawl l . The gear i carries a pin j^1 in position for lifting the pawl l out of engagement with the nose k^3 of the lever k . Furthermore the contact making finger h^2 is secured to and insulated 25 from the lever k . The gear e carries the second contact h^1 which is in the form of an insulated cam disk of spiral outline. Normally the finger h^2 and the disk h^1 are out of contact with each other, so that the 30 circuit of the electromotor r is interrupted, but they are adapted to be brought into engagement with each other for supplying energy to the motor, as will be described hereinafter.
- 35 The rear end of the lever k is in pin and slot engagement with a lever m^2 carrying a spring arm m^1 adapted to make contact with the balance m of the movement for temporarily arresting the clock when winding the 40 same.

- The tail of lever l is formed with gear teeth l^3 which are in mesh with a pinion n^2 secured to a spindle n^3 carrying a disk n^1 . The latter is movable at the rear of a hole n 45 made in the disk b and the dial plate and it shows two fields n^4 and n^5 of different colors say white and red either one of which is in position for covering the hole n and for indicating whether or not the clock is being 50 wound.

The operation of the winding mechanism is as follows:

- Normally the parts are in the positions shown in the figures and more particularly 55 in Fig. 2. The pawl l engages the nose k^3 of the lever k , the arm h^2 is out of contact with the disk h^1 , and the wire m^1 does not make contact with the balance m , so that the clock runs. This position of the parts is 60 indicated by the sector n^1 displaying a white field at the rear of the window n made in the dial plate. The disk h^1 does not take part in the movement of the work, because it is carried by the spring arbor e^1 . The 65 movement of the barrel is transmitted to the

work through the gear teeth d , as is known in the art. In addition the said gear teeth impart rotary movement to the gear i turning the same in anti-clockwise direction. At the time the clock is nearly run down 70 the pin j^1 carried by the gear i gets into engagement with the pawl l and carries the same along until the lever k is released. The sector n^1 is rocked for displaying the red field, and the lever k is thrown by its 75 spring towards the disk j and with its pin k^4 bearing on the circumference of the said disk at a point slightly in advance of the notch j^2 . As the clock continues its movement the pin j^1 gets into position for releasing 80 the pawl l which is rocked inwardly by its spring and on the outer face of the nose k^3 , the sector n^1 still displaying the red field. Upon further movement of the gear i the notch j^2 advances into position for engagement 85 by the pin k^4 , whereupon the lever k is rocked with its pin k^4 into the said notch. Thereby the wire m^1 is brought into contact with the balance m so as to arrest the movement, and the arm h^2 makes contact with 90 the disk h^1 for closing the circuit of the electromotor r .

By supplying energy to the electromotor the gear wheel e provided on the spring shaft is rotated in clockwise direction for 95 winding the clock and rotating the disk h^1 . The cam disk h^1 gradually rocks the lever k outwardly. When the arm h^2 arrives at the part of largest radius of the cam h^1 the lever k releases the pawl l and permits 100 the same to fall into initial position, and when the arm passes beyond the said part the lever k is thrown inwardly and into the position shown in Fig. 2, in which the motor 105 circuit is interrupted. However, the motor continues its rotation by its momentum, until the disk h^1 is substantially in the position shown in Fig. 2. By the last part 110 of the inward movement of the pawl l the sector n^1 is set into position for displaying the white field, thus indicating that winding is completed.

Should the wire m^1 fail to arrest the movement the gear i continues its movement until the rear wall of the notch j^2 makes 115 contact with the pin k^4 . Thereby the clock is arrested, so that it can not run down beyond the limit set by the winding mechanism.

As shown in Fig. 2 the lever k bears 120 through the pawl l on the pin j^1 for a comparatively long time, the face of the nose k^3 engaged by the pin j^1 being comparatively long. Practically only a short rocking movement of the pawl l is necessary for 125 releasing the lever k , the long face of the nose k^3 being shown in Fig. 2 only for clearness sake. In some cases I omit the wire m^1 arresting the balance m , in which case the clock is arrested by the rear wall 130

of the notch getting in contact with the pin k^4 , should the motor fail to wind the clock.

An important feature of the invention resides in providing a mechanism in which a clock of normal construction may be used after changing only one or two of its elements such as the spring arbor. By disposing the levers controlling the winding mechanism on the ring b and independently of the clock mechanism they may be as large as is desirable in view of convenience in the manufacture, and it is not necessary to construct the same with minute accuracy to insure exact operation, as would be the case when constructing the same as parts of the clock mechanism. Notwithstanding their large dimension they do not interfere with the running of the clock, because they are in engagement therewith only for a short period of time.

Another important feature resides in mounting the parts of the apparatus, viz., the clock, the motor and the winding mechanism independently of one another and so that either one of the parts may be separately repaired.

In Figs. 5 and 6 I have shown a modification in which the means for making and breaking the circuit of the electromotor are made in a different way. The general construction of the winding mechanism is the same as has been described with reference to Figs. 1 to 4, and the same reference characters have been used to indicate similar parts, so that it is not necessary to repeat the description of the said parts.

The disk j is driven together with the movement by the gear wheels d , i , and the lever k carrying the pin k^4 is normally held in inoperative position by the spring pressed pawl l , the latter being adapted to be rocked by the pin j^1 taking part in the rotation of the gear wheel i . As distinguished from the construction described with reference to Figs. 1 to 4 the circuit make-and-break device is mounted independently of the lever k and the spring barrel, and it consists of a contact h^3 and a spring arm h^4 adapted to be thrown into contact with the contact h^3 by the tail end of the lever k . For returning the lever l into normal position and interrupting the motor circuit, a spring pressed slide bar o is mounted in eyes o^1 , o^2 , the end of which is adapted for engagement with the lever k , and which carries an arm o^2 . The gear wheel e secured to the spring arbor carries a disk o^5 having a pin o^6 mounted thereon, which pin is adapted when winding the clock to engage the arm o^2 for shifting the rod o away from the lever k . The motor g is disposed at the side of the clock and its shaft drives the gear f through the intermediary of a worm gearing f^1 .

The operation of the winding mechanism

is as follows: Normally the parts are in the positions shown in Fig. 5 in which the lever k opens the motor circuit and the pin k^4 is out of contact with the disk j . The disk j takes part in the movement of the work, and when the clock has nearly run down the pin j^1 pushes the pawl l outwardly, so that the lever k is pressed inwardly by its spring with the pin k^4 bearing on the circumference of the disk j . Upon further movement of the disk j the notch j^2 gets into position in front of the pin k^4 , whereupon the lever k is rocked further inwardly so far that its tail closes the circuit make-and-break device h^3 , h^4 . In the meantime the pin j^1 has released the pawl l which is therefore pressed by its spring on the outer face of the lever k . The sector n^1 and the spring m^1 are operated in the manner described above. By closing the motor circuit the motor is started and the clock wound. The pin o^4 takes part in the rotary movement of the spring arbor, and it carries along the arm o^2 , and shifts the rod o rearwardly in opposition to the spring acting thereon. After it has passed the said arm the rod o is thrown to the left and against the lever k , which is thereby rocked out of engagement with the notch j^2 . Thereby the spring m^1 releases the balance m and the motor circuit is interrupted. The pawl l is rocked by its spring into the position for holding the lever k away from the disk j , and the lever k is pressed inwardly and on the pawl l by its spring.

I claim:

1. In a self-winding electric clock, the combination, with the clock movement, and electric winding means, of an energizing circuit for said winding means, a make-and-break device arranged in said circuit and including a spring-backed swinging beam, a second spring-backed swinging beam normally engaging the first beam and holding it under tension in position of circuit-breaking, means operating when the clock is run down to a definite extent and connected with said movement for swinging said second beam from its engagement with the first beam, and leaving the said first beam free to move under spring tension to circuit-closing position, and means connected with the winding mechanism for swinging the beam first named against spring tension back to its position of circuit-breaking.

2. In a self-winding electric clock, the combination, with the clock movement, and electric winding means, of an automatically actuated lever adapted to throw said winding means into and out of operation, a member normally holding said lever in position for throwing said winding means out of operation, means connected with the movement and normally out of engagement with said member and lever for setting the member into position for releasing said lever, means

- movable with said clock movement to hold said lever in an intermediate position until said member has been released from the setting means thereof, and means adapted to 5 be operated by the winding mechanism for setting said lever into position for being held by said member in position for throwing the winding mechanism out of operation.
3. In a self-winding electric clock, the 10 combination, with the clock movement, and electric winding means, of an automatically actuated lever adapted to throw said winding means into and out of operation, a member normally holding said lever in position 15 for throwing said winding means out of operation, means connected with the movement and normally out of engagement with said member and lever for setting the member into position for releasing said lever, a 20 disk rotatable with said clock movement and located in the position for arresting said lever in an intermediate position and having a portion in position for permitting said lever to move into position for throwing the 25 winding mechanism into operation after said member has been released from the clock movement, and means adapted to be operated by the winding mechanism for moving said lever into position for being held by said 30 member in position for throwing the winding mechanism out of operation.
4. In a self-winding electric clock, the 35 combination, with the clock movement, and electric winding means, of an automatically actuated lever adapted to throw said winding means into and out of operation, a member normally holding said lever in position 40 for throwing said winding means out of operation, means connected with the movement and normally out of engagement with said member and lever for setting the member into position for releasing said lever, a disk rotatable with said clock movement and located in position for arresting said lever 45 in an intermediate position and having a portion in position for permitting said lever to move into position for throwing the winding mechanism into operation after said member has been released from the 50 clock movement, and a spiral cam adapted to be operated by the winding mechanism for moving said lever into position for being held by said member in position for throwing the winding mechanism out of operation and having an abrupt portion permitting 55 said lever to move into position for throwing said winding means into operation.
5. In a self-winding electric clock, the 60 combination, with the clock movement, and electric winding means, of an automatically actuated lever adapted to throw said winding means into and out of operation, a member normally holding said lever in position 65 for throwing said winding means out of operation, means connected with the move- ment and normally out of engagement with said member and lever for setting the member into position for releasing said lever, a disk rotatable with said clock movement and located in position for arresting said lever in an intermediate position and having a portion in position for permitting said lever to move into position for throwing the winding mechanism into operation after said member has been released from the clock movement, and a spiral cam mounted on the spring arbor and adapted to be operated by the winding mechanism for moving said lever into position for being held by said member in position for throwing the winding mechanism out of operation and having an abrupt portion permitting said lever to move into position for throwing the winding mechanism into operation after said member has been released from the clock movement, and a spiral cam mounted on the spring arbor and adapted to be operated by the winding mechanism for moving said lever into position for being held by said member in position for throwing the winding mechanism out of operation and having an abrupt portion permitting said lever to move into position for throwing the winding mechanism into operation.
6. In a self-winding electric clock, the 85 combination, with the clock movement, electric winding means, and an energizing circuit therefor, of a spiral cam included in said circuit and operatively connected with the winding mechanism for being rotated thereby, a device included in the circuit and adapted to make contact with said cam for closing the electric circuit, a member normally holding said device out of contact with said cam, and means movable with the clock movement for setting said member into position for releasing the device, said cam being formed so as to return said device into position for being held by said member.
7. In a self-winding electric clock, the 95 combination, with the clock movement, electric winding means, and an energizing circuit therefor, of a spiral cam included in said circuit and operatively connected with the winding mechanism for being rotated thereby, a lever included in the circuit and adapted to make contact with said cam for closing the electric circuit, a member normally holding said lever out of contact with said cam, means movable with the clock 100 movement for setting said member into position for releasing the lever, said cam being formed so as to return said lever into position for being held by said member, a disk rotatable with the clock movement and located in position for arresting said lever in an intermediate position, said disk being formed with a portion located and formed so that said lever is free to move into engagement with said cam.
8. In a self-winding electric clock, the 110 combination, with the clock movement, and electric winding means, of mechanism controlled by the clock movement to throw said winding means into operation, means controlled by the winding mechanism to throw the winding means out of operation, and means operative when said mechanism has been actuated to arrest the clock movement.
9. In a self-winding electric clock, the 115

combination, with the clock movement, and electric winding means, of an automatically actuated lever adapted to throw said winding means into and out of operation, a member normally holding said lever in position for throwing said winding means out of operation, means connected with the movement and normally out of engagement with said member and lever for setting the member into position for releasing said lever, a disk rotatable with said clock movement and located in position for arresting said lever in an intermediate position and having a portion in position for permitting said lever to move into position for throwing the winding mechanism into operation after said member has been released from the clock movement, said portion having a shoulder adapted for arresting engagement with said disk, and means adapted to be operated by the winding mechanism for moving said lever into position for being held by said member in position for throwing the winding mechanism out of operation.

10 10. In a self-winding electric clock, the combination, with the clock movement, and electric winding means, of an automatically actuated lever adapted to throw said winding means into and out of operation, a member normally holding said lever in position for throwing said winding means out of operation, means connected with the movement and normally out of engagement with said member and lever for setting the member into position for releasing said lever, a disk rotatable with said clock movement and located in position for arresting said lever in an intermediate position and having a portion in position for permitting said lever to move into position for throwing the winding mechanism into operation after said member has been released from the clock movement, means operative when said lever engages in said portion for arresting the clock movement, and means adapted to be operated by the winding mechanism for

15 20 25 30 35 40 45

moving said lever into position for being held by said member in position for throwing the winding mechanism out of operation.

11. In a self-winding electric clock, the combination, with the clock movement, and electric winding means, of mechanism controlled by the clock movement to throw said winding means into operation, means controlled by the winding mechanism to throw the winding means out of operation, and means connected with said mechanism for indicating that the mechanism has been operated for throwing the winding means into operation. 55 60

12. In a self-winding electric clock the combination, with a clock movement including a constantly rotating gear wheel of a second gear wheel in mesh with the first, and rotatable in unison with the first, and normally free of restraint in its response to the rotation of the first, a movable member bearing a contact piece, and means including a member borne by said second gear wheel for effecting movement of said movable member when said second gear wheel in the course of rotation has reached a predetermined point. 65 70

13. In a self-winding electric clock the 75 combination, with a clock movement including a constantly rotating gear wheel, of a second gear wheel in mesh with the first and rotatable in unison with the first and normally free of restraint in its response to the 80 rotation of the first, a spring-backed movable member bearing a contact piece, and a latch normally holding said movable member retracted, said second gear wheel bearing a latch-engaging abutment. 85

In testimony whereof I hereunto affix my signature in the presence of two witnesses.

FERDINAND BUSSE.
